Howard & Son,

UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,409, dated February 11, 1873.

To all whom it may concern:

Be it known that I, FREDERICK WINK, of the city and county of Philadelphia and State of Pennsylvania, have invented a Design for a Shawl-Pattern, of which the following is a specification:

The principal features of my design for a shawl-pattern, which is fully represented in the accompanying drawing, are the stripes A and B and the intervening body C, the latter being either plain or mottled, as shown. The stripe A is composed of a series of narrow stripes, ribs, or bars, some of which are blended together by shading, as shown, and the said stripe is ornamented by a central rib, a, through the center of which extends a longitudinal row of alternate dots and short bars, and by a series of narrow ribs, b, each com-

posed also of a row of alternate dots and bars. The stripe B is composed of a series of parallel minor stripes, and has a central rib, d, ornamented by a series of longitudinal rows of alternate dots and bars.

Irrespective of the colors employed, I claim—

1. The design for the stripe A, as shown.
2. The design for the stripe B, as shown.
3. The design for the whole pattern, as shown.

In testimony whereof I have signed my name to this specification in the presence of two subscribing witnesses.

FRED. WINK.

Witnesses:

WM. A. STEEL,
HUBERT HOWSON.
